UNITED STATES PATENT OFFICE

99,395

DESIGN FOR A COMBINED LAMP AND MAGAZINE STAND

John H. Jewett, Detroit, Mich.

Application October 1, 1935, Serial No. 58,783

Term of patent 7 years

To all whom it may concern:

Be it known that I, John H. Jewett, a naturalized citizen of the United States, residing at Detroit, in the county of Wayne and State of Michigan, have invented a new, original, and ornamental Design for a Combined Lamp and Magazine Stand, of which the following is a specification, reference being had to the accompanying drawing, forming part thereof.

I claim:

The ornamental design for a combined lamp and magazine stand, as shown.

In testimony whereof I hereunto affix my signature.

JOHN H. JEWETT.
